DESK SET

Christian Hansen, Woodcliff, N. J.

Application June 3, 1935, Serial No. 24,621

9 Claims. (Cl. 120—108)

This invention relates to desk sets for writing instruments and particularly to a holder for writing instruments having a uniform diameter throughout its length and arranged at the entrance thereof to yieldingly engage and support the writing instrument in the holder, and it is an object of the invention to provide such a desk set which is attractive in appearance and inexpensive to manufacture.

Another object of the invention is to mount the writing instrument holder on a supporting base to permit the positioning of the holder whereby the entire upper face of the supporting base is exposed and unobstructed by the holder and the writing instrument engaged therein.

A further object of the invention is to limit the movement of the writing instrument holder away from the upper face of the supporting base.

A still further object of the invention is to provide a holder for fountain pens arranged to cooperate with the neck portion of a fountain pen engaged therein to seal the pen from the atmosphere without supporting the fountain pen by said neck portion.

It is another object of the invention to provide means to actuate a writing instrument holder to various positions relative to its supporting base.

It is a further object of the invention to yieldingly retain a writing instrument holder in adjusted positions on a supporting base and permit regulating of said yielding retention of the holder.

Further objects and advantages will herein-after appear.

In the drawing accompanying and forming a part of this application, Figure 1 is an elevational view of a desk set forming an embodiment of this invention with the writing instrument holder partly in section and a fountain pen engaged therein to show the atmospheric seal between the holder and the neck portion of the fountain pen and the yielding or resilient supporting of the fountain pen by the mouth of the holder.

Figure 2 is a plan view of the desk set showing the writing instrument holder in the dotted line position shown in Figure 1 and the upper surface of the supporting base clear of any obstructions.

Figure 3 is a view looking at the right of Figure 1.

Figure 4 is a fragmentary sectional view taken on the line 4—4 of Figure 3 looking in the direction of the arrows to show the mounting of the writing instrument holder and means to yield-

ingly retain the holder in adjusted position relative to the supporting base.

Figure 5 is a perspective view of the desk set showing a modification of mounting the writing instrument holder on the supporting base; 5 and

Figure 6 is a sectional view taken on the line 6—6 of Figure 5 looking in the direction of the arrows and showing the modified form of mounting.

Like characters will designate like parts throughout the specification.

In carrying out the embodiment of the invention as illustrated in Figures 1 to 4, inclusive, of the drawing, there is provided a flat supporting base or plate 1 of suitable material, such as stone, imitation stone or metal, and of any suitable shape in plan, shown in the present instance as being of square form. To enhance the appearance of the supporting base the corners or angle portions thereof are cut off, as at 8, and the upper marginal edge is beveled, as at 9. The underface of the base may be covered by a layer of fabric, such as felt, adhesively attached to the base, which covering will prevent the marring of a highly polished supporting surface, such as a desk. The upper face of the base may be arranged as a receptacle for paper fasteners and the like by dishing or hollowing out the center portion of said face.

The desk set of the present invention is particularly designed for supporting a fountain pen, as indicated at P, having a barrel portion b and a neck portion n intermediate the barrel and a pen p. The fountain pen is releasably supported on the base 1 by a holder comprising a tubular body 10 of resilient metallic material formed from tubing of uniform diameter and having one end partly closed by swaging the material inward at said end, as at 11. The opposite end is formed as an expansible open end for yieldingly engaging the barrel of the pen by a series of equidistantly spaced slits 12 disposed about the circumference of said end of the tubular body and extended from said end to a point intermediate the ends of the tubular body whereby the partially closed end is arranged with a portion of uniform diameter for the engagement of the neck portion n of the pen, as clearly shown in Figure 1, the diameter of the closed end portion of the holder being such as to permit the ready engagement of the neck portion therein and form with the neck a seal to prevent access of the atmosphere to the pen p and the drying of ink at the pen. The slits 12 arranged the open

end of the tubular body with a series of resilient fingers 13 adapted to yieldingly engage the barrel b as the fountain pen is inserted in the holder, and to facilitate such insertion of the pen the free ends of the resilient fingers are flared outwardly, as at 14. This form of fountain pen holder adapts the desk set for fountain pens having barrels of varying diameters, and as the neck portion of all fountain pens are of the same diameter, it will not be necessary to change the diameter of the partially closed end of the holder or the mean diameter of the tubular stock from which the holder is formed.

The holder 10 is mounted on the base 7 to have movement from one side of the base to an adjacent side in an arc above the upper face of the base by a shaft 15 rotatably mounted in a sleeve 16 fixedly engaged in the mouth or entrance end of a cylindrical recess 17 extending into the base 7 parallelly of and adjacent the upper face of the base from a cut off angle portion 8 thereof diagonally toward the opposite angle portion 8 and terminating within the base. The rotation of the shaft is yieldingly retarded by a coil spring 18 on a portion of the shaft 15 within the recess 17 and compressed between the sleeve 16 and a collar 19 fixed on the end of the shaft 15 by a portion of an arcuate bend 20 in the shaft exterior of the base 7 engaging the sleeve 16, the tension of the spring urging the bent portion 20 of the shaft into engagement with the sleeve to frictionally hold the shaft against rotative movement. The tension of the spring may be adjusted by varying the length of the portion of the shaft 15 within the recess 17. The holder is mounted on the bent end of the shaft by engaging the end of the shaft in the opening in the partially closed end of the holder 10 and secured therein in any suitable manner, as by soldering, so that said end 40 of the holder is completely closed. The arc of the bent portion 20 of the shaft 15 is such as to permit the adjusting of the holder 10 into juxtaposed relation to either of the sides 7' of the base extending from the angle portion 8 in which the shaft is mounted, as shown in Figure 2, and to position intermediate said sides to extend at an acute angle to the upper face of the base in axial alignment with the shaft 15 and in position to receive a pen, as shown in Figures 1 and 3. In 50 the Figure 2 position of the holder, downward movement of the holder will engage the holder with either of the sides 7' and limit said movement due to the mounting of the shaft adjacent the upper face of the base.

In Figures 5 and 6, there is shown modified means for mounting the holder 10 on a base similar to the base 7 shown in Figures 1 to 4, inclusive, but preferably of slightly greater thickness with one of the angle portions 8 extending 60 from the upper face for only a portion of the thickness of the base to form a shoulder 21 extending parallelly of the face of the base and below a bore in the base extending from said angle portion 8 through the diagonally opposite angle portion and arranged with the opposite end portions of different diameters, as at 22 and 23, with the portion 22 of largest diameter opening to the angle portion above the shoulder 21 and the portion of smallest diameter opening to the 70 diagonally opposite angle portion, as shown in Figure 6. A shaft 24 of greater length than the length of the bore and of a diameter substantially equal to the smallest diameter of the bore is rotatably supported in said portion of the bore.

To the end of the portion of the shaft projecting

from the portion of the bore of largest diameter, there is secured an arm 25 in the form of a plate of a width corresponding to the width of the angle portion 8, said arm being mounted adjacent one end on the shaft so that said end will be juxtaposed to the shoulder 21 with the arm contiguous to the angle portion 8 and the opposite end portion extending above the upper face of the base when the arm extends parallelly of said angle portion. The extending end portion 10 of the arm is bent to project laterally of the base at an obtuse angle to the upper face thereof, as shown at 26 in Figure 6. The holder 10 is mounted on the bent end of the arm 25 by any suitable means, such as a rivet secured in an 15 opening in the arm and the partially closed end of the holder, as shown at 27 in Figure 5, the rivet closing the partially closed end of the holder. The bent portion 26 of the arm will position the holder to extend at an acute angle to 20 the upper face of the base and lie contiguous to adjacent sides 7' thereof. The shaft 24 is retained in the base 7 by a nut 28 screw threaded onto the end of the shaft extending exteriorly of the base from the bore portion 23 of smallest 25 diameter with a washer 29 interposed between the nut and the adjacent angle portion 8 to permit the rotation of the shaft by the nut when the nut is securely engaged on the shaft to adjust the holder 10 to positions juxtaposed to the adjacent sides of the base forming the angle portion 8 having the shoulder 21, as shown in Figure 5, and to position above the upper face of the base to receive a fountain pen, as shown in Figure 6. To facilitate applying the nut to the shaft 30 and rotative adjustment of the shaft, the peripheral portion thereof is knurled. To yieldingly retain the holder in adjusted position, a coil spring similar to the spring 18 is engaged on the portion of the shaft 24 in the portion of 40 enlarged diameter 22 of the bore in the base and compressed between the arm 25 and the shoulder formed at the juncture of the portions of different diameters of the bore, as clearly shown in Figure 6. As clearly shown in Figure 5, 45 the movement of the holder 10 to position juxtaposed to the sides of the base is limited by the sides of the arm 25 abutting the shoulder 21. In the arrangement of parts shown in Figures 5 and 6, the holder 10 may either be adjusted to its various positions by the nut or by grasping the holder itself. The nut 28 may be permanently retained on the shaft 24 by peening over the end of the shaft extending from the nut.

It will be obvious that the holder 10 is capable 55 of supporting a pencil as well as a fountain pen shown in the drawing, and that various modifications may be made in construction and arrangement of parts without departing from the scope of the invention and portions of the invention 60 may be used without others and come within the scope of the invention.

Having thus described my invention, I claim:

1. In a desk set, a flat base, a shaft rotatably mounted in the base to rotate on an axis extending longitudinally of the base and one end projecting laterally from the base, a holder for a writing instrument fixed on the shaft to extend at an angle to the upper face of the base and contiguous to the sides of the base by the rotation of the shaft, and a spring coiled about the shaft within the base and compressed between the shaft and base to yieldingly retard the rotation of the shaft and retain the holder in adjusted position.

2. In a desk set, a flat rectangular base having a recess extended therein from an angle portion of the base in a direction toward the opposite angle portion, a shaft rotatably mounted in said recess with an end thereof extending from the base, a fountain pen holder fixed on the extended end of the shaft and adapted by the rotation of the shaft to be positioned to extend at an angle above the upper face of the base in position to receive a fountain pen and contiguous to the sides of the base forming the angle portion into which the recess is extended, a sleeve engaged in the recess to rotatably support the shaft, a collar fixed on the end of the shaft within the recess, a spring coiled about the shaft and compressed between the sleeve and collar, and the extended portion of the shaft bent in angular relation to the base and engaged with the base under the force of the spring to yieldingly retard the rotation of the shaft and retain the pen holder in adjusted position.

3. In a desk set, a flat rectangular base, a shaft rotatably mounted in the base to extend parallelly of and adjacent to the upper face of the base and having one end extended from and bent in an arcuate direction relative to an angle portion of the base, and a pen holder fixed on the extended bent end of the shaft adapted to be positioned to extend at an acute angle to the upper face of the base and contiguous to the sides of the base forming the angle portion with the holder impinging said sides of the base and limiting the movement of the holder and the rotation of the shaft.

4. In a desk set, a flat rectangular base, a shaft rotatably mounted in the base with the opposite ends projecting from diagonally opposite angle portions of the base, a pen holder fixed to one of the projecting ends of the shaft to be adjusted by the rotation of the shaft to positions in angular relation to the upper face of the base and contiguous to the sides of the angle portion from which said end of the shaft projects, and means adjustably engaged on the opposite end of the shaft to retain the pen holder in adjusted positions.

5. In a desk set as claimed in claim 4, a spring

coiled about the shaft to yieldingly retard the rotation of the shaft.

6. A desk set as claimed in claim 4, wherein the means adjustably engaged on the opposite end of the shaft is arranged with a manipulating portion to facilitate the rotation of the shaft and the positioning of the pen holder.

7. In a desk set, a flat rectangular base having a bore extending diagonally therethrough terminating at opposite angle portions of the base with the opposite end portions of different diameters, a shaft of a diameter substantially equal to the smallest diameter of the bore and mounted in the bore with the opposite ends projecting from the base, a pen holder fixed on one of the projecting ends of the shaft to participate in the rotation of the shaft, means mounted on the opposite end of the shaft and adapted to rotate the shaft and position the pen holder in angular relation to the upper face of the base and contiguous to the sides of the base adjacent the connection between the shaft and pen holder, and a spring coiled about the shaft within the portion of the bore of largest diameter to yieldingly retain the shaft against rotation.

8. In a desk set, a flat rectangular base having an angle portion arranged with a shoulder extending intermediate and parallelly of the faces of the base, a shaft rotatably mounted in the base with an end projecting from said angle portion in spaced relation to the shoulder, an arm fixed to the projecting end of the shaft flush with the angle portion and the sides thereof being adapted to engage the shoulder and limit the rotation of the shaft, and a fountain pen holder carried by the arm.

9. A desk set as claimed in claim 8, wherein the arm is of a length to extend above the upper face of the base when the sides thereof are perpendicular to the shoulder and the portion extending above the face of the base being bent to extend at an obtuse angle to said face and position the pen holder to extend at an acute angle to the face of the base and to positions contiguous to the sides of the base adjacent said angle portion.

CHRISTIAN HANSEN.
